(57) **CLAIM**

We claim the ornamental design for a folding ring stove, as shown and described.

DESCRIPTION

FIG. 1 is a perspective view of a folding ring stove in assembled configuration with four air flaps in a lowered position and four alternating air flaps in a raised position showing our new design;

FIG. 2 is an exploded perspective view thereof, illustrating a base and a ring insert in a disassembled configuration;

FIG. 3 is a left-side elevational view thereof, illustrated in the assembled configuration with four air flaps in the lowered position and four alternating air flaps in the raised position, the right-side elevational view, front elevational view, and rear elevational view all being a mirror image thereof;

FIG. 4 is a left-side elevational view of the ring insert thereof, the right-side elevational view, front elevational view, and rear elevational view all being a mirror image thereof;

FIG. 5. is a left-side elevational view of the base thereof, illustrated with four air flaps in the lowered position and four alternating air flaps in the raised position, the right-side elevational view, front elevational view, and rear elevational view all being a mirror image thereof;

FIG. 6 is a top plan view of the ring insert;

FIG. 7 is a bottom plan view of the ring insert;

FIG. 8 is a bottom plan view of the base, illustrated with four air flaps in the lowered position and four alternating air flaps in the raised position; and,

FIG. 9 is a top plan view thereof.

FIGS. 4–9 are shown separate for clarity of illustration. The claim is fully shown in FIGS. 1–3.
